EMANUEL HOLEK, OF BRUNN, CZECHOSLOVAKIA, ASSIGNOR TO THE FIRM CESKO-SLOVENSKA ZBROJOVKA AKCIOVA SPOLECNOST V BRNE, OF BRUNN, CZECHOSLOVAKIA

FIRING MECHANISM FOR AUTOMATIC FIREARMS

Application filed June 18, 1929, Serial No. 371,786, and in Czechoslovakia June 20, 1928.

This invention relates to firing mechanisms for automatic fire-arms and has primarily for its object to provide a novel construction of a firing mechanism of this kind, permitting to improve the fire-arm, especially in regard to better readiness for service. A further object of my invention consists in providing a special construction of a firing mechanism permitting, in addition to automatic firing, also the firing of single shots. A further object of my invention is the provision of a safety device of specific construction which permits proper locking of the firing mechanism in operative as well as in inoperative position of the trigger-mechanism.

In the accompanying drawing I have shown in the form of diagrammatical representations a few embodiments of my invention, Fig. 1 being a side-view partly in section, showing the firing mechanism after firing of the last shot, Fig. 2 a view similar to Fig. 1 showing the firing mechanism after depression of the feeding device, Fig. 3 a further view showing the devices of Figs. 1 and 2 after actuation of the firing mechanism, Fig. 4 a view showing especially the action of the rear elevation of the breech and Fig. 5 a view showing especially the action of the front elevation of the breech. Fig. 6 shows my new firing mechanism together with a specific safety device in inoperative position with omission of the breech, and Fig. 7 the firing mechanism in a position in which a double locking safety device comes into action. Fig. 8 shows the firing mechanism in position after being locked by said safety device, Fig. 9 is a detail view of said safety device, and Fig. 10 a section according to line X—X of Fig. 8 as seen from the left towards the right.

Referring now more particularly to the drawings, the firing mechanism according to my invention is provided in the well-known manner underneath the breech 1 of the automatic fire-arm, while the feeding device 2 co-operates with said breech. The firing mechanism proper consists of the hammer 3 mounted swingably around the pivot 7 and actuated by the spring 8. The hammer 3,

more particularly, engages by means of the nose 3a thereon with the anchor-shaped trigger-lever 5 at a place intermediate the two arms thereof, the nose 3a of the hammer 3 co-operating with the nose 5a of the trigger-lever 5, as indicated in Fig. 1. The rear part of the anchor-shaped trigger-lever 5 is provided with an interrupter 6 in the form of a double-armed lever fulcrumed to the trigger-lever as indicated at 9, said interrupter being under the action of a spring 8. The rearward extension 10 of the trigger-lever 5 rests upon the arm of the trigger 4. The interrupter 6 is adapted to co-operate at its under end with the nose 3b of the hammer 3, said nose 3b being positioned oppositely to said nose 3a.

Upon the under surface of the breech 1, as may be seen from Figs. 1 to 5, there is provided a recess 1c which forms part of the catch and control mechanism for the hammer 3. According to my invention an elevation 1a is provided in front of said recess 1c, said elevation presenting at its front part an oblique guide surface *o* and at its rear part a sliding surface *p* which forms a part of said recess 1c. The elevation 1a projects somewhat from the under edge of said recess 1c. In front of the oblique guide surface *o* there is provided a somewhat longer guide surface *m* which is of an inclination opposite to that of the surface *o*. In the rear of the recess 1a there is further provided a guide surface *r* which is downwardly inclined towards the rear and extends almost as far as to the rear end of the breech, in such a manner to form an elevation 1b near the rear end *S* of the breech.

The detail construction of the aforescribed parts of the firing mechanism will be apparent from the hereinbelow description of the mode of operation of said mechanism. After the last shot has been fired, that is, in empty condition of the cartridge-magazine, the cartridge feeding device 2 will be pushed in front of the breech 1 which during firing has been opened by the effect of the recoil. The cartridge feeding device 2 will thus lock the breech 1 in open condition thereof as represented in Fig. 1. The hammer 3

rests with its head upon the under part of the sliding surface p of the front elevation $1a$ on the breech 1 , the nose $3a$ of the hammer 3 freely engaging from below with the nose $5a$ on the trigger-lever 5 . After the magazine has been loaded the cartridge feeding device 2 will be in depressed condition, and the breech is now released so that it will slightly move towards the front, the head of the hammer 3 now sliding upon the surface p which forms part of the elevation $1a$ on the breech 1 , until the hammer 3 snaps into the recess $1c$, this causing the breech to be locked in open position as represented in Fig. 15. 2. In this condition of the firing mechanism the noses $3a$ and $5a$ will be in engagement with each other. Upon pulling the trigger 4 the trigger-lever 5 will be rocked and the nose $5a$ thereon will pull the hammer 3 down 20 until the head of the hammer comes out of engagement with the recess $1c$ on the breech 1 . Now the breech 1 is released and may further be moved forward by action of a spring causing a new cartridge to be pushed 25 out of the magazine into the loading space. Simultaneously therewith the nose $5a$ on the trigger-lever 5 will come out of engagement with the nose $3a$ on the hammer 3 as indicated in Fig. 3. Upon continued forward 30 motion of the breech 1 the oblique surface r which forms part of the rear elevation $1b$ on the breech will exert a pressure on the hammer 3 and cause depression of the same until the nose $3b$ will come in engagement 35 with the under end of the interrupter actuated by the spring 8 . The interrupter 6 now will retain the hammer 3 in this position so that the latter is prevented from moving into the rear of the breech 1 which now commences 40 its closing motion. During closing of the breech, therefore, premature firing will be safely prevented. In like manner there will be prevention against firing a series of shots so that the fire-arm is in condition for the 45 automatic firing of single shots, the trigger being continuously pulled for this purpose. When re'easing the trigger, the spring 8 will rock the trigger-lever 5 in clockwise sense, the spring 8 now acting upon the trigger 4 50 and the trigger-lever 5 by the intermediary of the interrupter 6 which rests with its upper part 11 upon the upper surface of the rearwardly extending arm 10 of the trigger-lever 5 . The interrupter 6 now is disengaged 55 from the nose $3b$ of the hammer 3 , thus catching up the hammer 3 when rearwardly swinging. The hammer now will only swing slightly in counter-clockwise sense until the noses $3a$ and $5a$ will come into engagement with 60 each other, while the front side of the hammer 3 will rest upon the rear oblique surface S which forms part of the elevation $1b$ on the rear part of the breech 1 , as shown in Fig. 2. If the trigger has been pulled before the rear elevation $1b$ of the breech has

come in position above the hammer, the elevation $1b$ will likewise depress the hammer, 3 , the nose $3a$ on the hammer, however, coming now at once into engagement from below with the nose $5a$ on the trigger-lever 5 , so that the interrupter 6 will be rocked against the action of the spring 8 without the right-hand nose $3b$ of the hammer 3 coming into engagement with the under end of the interrupter 6 . The respective parts now will at once come into the position which they have assumed after releasing the trigger, as above described.

By the aforescribed motions of the parts of the firing mechanism the first cartridge had been moved out of the filled cartridge magazine into the loading space. Apparently, in this case the trigger must be pulled twice in order to fire a new shot. More particularly when pulling the trigger the first time, the hammer 3 which engages with the recess $1c$ of the breech 1 will cause to release the breech to permit loading, while pulling the trigger a second time will cause the firing of a shot by releasing the hammer 3 which is kept in tensioned condition by the trigger-lever 5 .

In order to avoid the necessity of pulling the trigger twice for each shot to be fired, there is provided the elevation $1a$ in front of the recess $1c$, said elevation $1a$ consisting of two oblique surfaces o and p . If the breech after ejection of the empty cartridge cases has again returned into firing position, at first the hammer 3 will be slightly lifted in accordance with the gradual increase of the height of the surface m . Thereupon, however, the hammer 3 will be quickly depressed by action of the surface o which is of greater obliquity, so that a heavy impact will be given to the hammer in clockwise sense. This impact will be so effective that the hammer will remain in retracted position for some short time which is sufficient to cause the recess $1c$ to slide past the hammer without engaging therewith. In this manner the hammer will be unable to lock the breech and come in sliding engagement with the oblique surface r of the rear elevation $1d$. In order to securely attain this, the front elevation $1a$ is somewhat higher than the under edge of the recess $1c$. The hammer 3 will be pressed backward by action of the elevation $1b$ into tensioned, locked position in the same manner as has been above described. More particularly, the hammer 3 in pulled condition of the trigger will be locked by the interrupter 6 and in released condition of the trigger by the nose $5b$ so that said hammer is prevented from following the motion of the breech which is now closing, thus preventing the firing of successive shots.

After complete closing of the breech, therefore, the trigger 4 must be pulled anew for each shot to be fired. Apparently, any desired number of shots may now be fired by merely pulling the trigger once for each shot.

As Figs. 6-10 show, the trigger mechanism is provided with a resistance member co-operating with the hammer 3, said resistance member coming into action during operation 5 of the trigger and before the hammer 3 is in released condition. This resistance member is provided on the trigger-lever 5 as shown in Figs. 6-10 in form of the interrupter 6 which is constructed to constitute a stop 15 10 mounted resiliently yielding upon the trigger-lever, said stop being at a distance 16 from the hammer 3 in inoperative condition of the trigger mechanism. During the first phase of motion of the several parts of the 15 trigger mechanism all of said parts must be moved to a certain extent in accordance with said distance 16, whereupon the resiliently yielding resistance 15 will come into action. It may be noted that the aforescribed mode 20 of controlling the motion of the hammer by means of the breech will in no way be unfavorably affected by the provision of said resiliently yielding resistance. Moreover, the aforescribed interrupter which is constructed to act as a resistance member will permit firing of individual shots by means of automatic fire-arms.

If the trigger mechanism, for instance, is in the condition as shown in Fig. 6, a pulling 30 of the trigger 4 will cause the interrupter 6 to move together with said resistance member or stop 15 in the direction towards the nose 3b on the hammer 3, that is said resistance member will move through the distance 16. 35 In this condition the several parts of the trigger-mechanism may be very easily operated. In the position shown in Fig. 7, that is after the several parts of the trigger-mechanism have moved through the distance 16, 40 the resistance member or stop 15 engages with the nose 3b of the hammer 3. The resistance member 15 will now come into action with the effect that intermediate the position of the hammer shown in Fig. 7 and the position in which the hammer is fully released 45 there will be required an increased force in order to operate the several parts of the trigger-mechanism. This resistance which will come automatically into action will indicate 50 to the shooter that the several parts of the trigger-mechanism are positioned closely in front of its condition of release. By this the shooter will be given the possibility to take aim still more carefully and thereupon 55 fire the shot by exerting a short pull on the trigger. In the constructions shown herein the resistance within the firing mechanism is produced by the interrupter 6, it is of course also possible to use a special resistance 60 body which is mounted resiliently yielding upon the trigger-lever 5.

The trigger 4 is shown in Figs. 6 to 10 in a modified construction which forms part of this invention. According to Figs. 6 to 10 65 the trigger is provided with a forwardly pro-

jecting arm 20, a safety or locking device 21 being provided within the range of swinging motion of said arm 20. This safety device according to Figs. 6 to 10 consists of a rotatably mounted bolt 21 which is provided with a recess or cut-away portion 22. The bolt 21 is further equipped with a handle 25 and a resilient pawl 26 which co-operates with ratchets 27 and 28. The bolt 21, moreover, is provided with a ring-shaped groove 70 75 80 85 90 95 100 105 110 115 120 125 130

In the position of the bolt 21 shown in Figs. 6 and 7, that is in a position of the handle 25 which causes engagement of the pawl 26 with the ratchet 28, the trigger-mechanism will be in unlocked condition ready for firing. The trigger 4 may now be pulled, the recess 22 permitting free motion of the arm 20. In order to lock the trigger-mechanism, it will only be necessary to swing the handle 25 of the safety or locking device into the position shown in Fig. 9, this causing the pawl 26 to engage with the ratchet 27 which will keep the safety device in operative condition. The bolt 21 moreover will provide a safety device adapted to lock the trigger 4 not only in its position of rest—which position is shown in dash-dotted lines in Fig. 8—but also in operative position, that is after being pulled, as shown in full lines in Fig. 8. For this purpose a stop 31 is used, said stop being formed by the wall of the casing 33 which serves for the reception of the lock of the fire-arm. The stop 31, however, may also be constructed in the form of a special member which is fixed within the lock-casing 33. The provision of a safety locking device for the trigger 4 will be especially of importance for purposes of testing fire-arms as well as for purposes of repairs. In this locked or safety position of the trigger, the cartridge magazine may be gradually emptied and the fire-arm rendered inoperative.

It may be noted that the aforescribed safety device for the trigger will in no way affect the mode of controlling the motion of the hammer by the motion of the breech. Also, when using said safety device, the action of the interrupter 6 may fully be retained, that is the trigger, when locked in pulled condition, will permit the hammer 3 or the nose 3b thereon to be caught up and locked by said interrupter.

The herein described firing and trigger mechanisms are only examples of the construction according to my invention and various changes may be made thereon without

departing from the principles of my invention or sacrificing any advantages thereof.

I claim:

5. 1. A firing mechanism for automatic fire-arms having a breech which is retained in open condition by a device adapted to actuate the priming bolt, said mechanism comprising control means associated with said breech, said control means being adapted to prevent 10 retention of said breech by said device during rapid closing motion of said breech.
15. 2. A firing mechanism for automatic fire-arms having a breech which is retained in open condition by a hammer, said mechanism comprising control means associated with said breech, said control means being adapted to prevent retention of said breech by said hammer during rapid closing motion of said breech.
20. 3. Mechanism as specified by claim 1 having the control means provided in the direction of closing motion of the breech in front of a depression provided on said breech, said depression being adapted to receive the device which serves for actuation of the priming bolt.
25. 4. Mechanism as specified by claim 2 in which the control means consists of two elevations, one provided in front and the other 30 in the rear of a depression on said breech, said elevation in front of said depression being of a greater height than said elevation in the rear of said depression.
35. 5. Mechanism as specified by claim 2 in which the control means consists of two elevations, one provided in front and the other in the rear of a depression on said breech, said elevation in front of said depression being of a greater height than said elevation in 40 the rear of said depression, and a sliding surface arranged intermediate said depression and said control means.
45. 6. Mechanism as specified by claim 2, in which an elevation is provided at the rear end of the breech, said elevation permitting to press the hammer of the fire-arm back into safety position.
50. 7. Mechanism as specified by claim 2, said mechanism comprising a double-armed trigger-lever, catches provided in opposition to each other on both arms of said lever, the hammer being provided with noses adapted to co-operate with said catches to permit locking of said hammer, when depressed by the 55 control means on the breech, in operative as well as in inoperative condition of said mechanism.
60. 8. Mechanism as specified by claim 2, said mechanism comprising a trigger provided with an arm, and a safety device arranged within the range of motion of said arm, said safety device being adapted to lock said trigger in operative as well as in inoperative condition.
65. 9. Mechanism as specified by claim 2, said

mechanism comprising a trigger provided with an arm, and a safety device arranged within the range of motion of said arm, said safety device consisting of a movably mounted bolt having a cut-away portion permitting swinging motion of said trigger.

10. Mechanism as specified by claim 2 said mechanism comprising a trigger provided with an arm, and a safety device arranged within the range of motion of said arm, said safety device being adapted to lock said trigger in operative as well as in inoperative condition, a stop provided within the range of swinging motion of said arm, said stop adapted to lock said trigger in conjunction with said safety device.

11. Mechanism as specified by claim 2, said mechanism comprising a trigger provided with an arm, and a safety device arranged within the range of motion of said arm, said safety device being adapted to lock said trigger in operative as well as in inoperative condition, and a stop provided within the range of swinging motion of said arm, said stop being formed by a part of the wall of the lock-casing of the fire-arm and adapted to lock said trigger in conjunction with said safety device.

12. Mechanism as specified by claim 2, said mechanism comprising a trigger-lever, a resistance body mounted on said trigger-lever and adapted to co-operate with the hammer to come into effect in operative position of said trigger-lever prior to releasing said hammer, an interrupter associated with said trigger-lever, said hammer and said trigger-lever being adapted to co-operate in independence from the breech and said interrupter.

13. Mechanism as specified by claim 2, said mechanism comprising a trigger-lever, a stop resiliently mounted on said trigger-lever at some distance from the hammer and adapted to co-operate therewith, an interrupter associated with said stop, said hammer and said trigger-lever being adapted to co-operate with each other in independence from the breech and said interrupter.

14. Mechanism as specified by claim 2, said mechanism comprising a trigger-lever, a stop resiliently mounted on said trigger-lever at some distance from the hammer and adapted to co-operate therewith, said hammer and said trigger-lever being adapted to co-operate with each other in independence from the breech and said stop.

In testimony whereof I affix my signature.

EMANUEL HOLEK.
